W.S. Hunkins
Atty's

UNITED STATES PATENT OFFICE.

WILLIAM S. HUNKINS, OF LOS ANGELES, CALIFORNIA.

HOSE-SUPPORTER.

1,398,486.

Specification of Letters Patent. Patented Nov. 29, 1921.

Application filed December 14, 1920. Serial No. 430,621.

To all whom it may concern:

Be it known that I, WILLIAM S. HUNKINS, a citizen of the United States of America, residing at Los Angeles, California, have 5 invented a new and useful Hose-Supporter, of which the following is a specification.

My invention relates particularly to improvements in devices such as covered by my Patent No. 1,354,485, of October 5, 1920.

10 The main object of my present invention is to construct a simple and inexpensive but reliable device for affording a bearing or bushing adapted to be secured to a corset, waist, or similar garment, and from which 15 the hose supporter is to depend. In my former patent, I broadly claimed certain combinations and illustrated several forms of bushings. I have in said patent specifically claimed a bushing adapted to be connected to what is commonly known as a 20 folded tape. The bushing of my present invention is applicable to any form of tape, and I have particularly sought to construct the bushing in such manner that when 25 secured to the tape at the factory, it can be shipped and handled without becoming accidentally disengaged. In other words, a tape and its bushing may be assembled at the factory and sold as an article of manufacture to be readily attached by anyone to 30 the corset or waist, or other garment desired.

Figure 1 illustrates my invention in its preferred form, the same being a front view of the device attached to the fragment of 35 a corset or waist, and with a hose supporter connected thereto.

Fig. 2 is a perspective view of the tape and bushing of Fig. 1.

Fig. 3 is a longitudinal sectional view of 40 the tape and bushing.

Fig. 4 shows the tape and bushing before their assembly, and in dotted lines, an intermediate stage of the assembly.

Fig. 5 is a sectional view at the intermediate stage of assembly and before the bushing is rolled or formed into shape.

Fig. 6 shows a somewhat different method of securing the bushing to the tape.

Fig. 7 is an outline view of the blank 50 from which the bushing of Fig. 6 is to be formed.

Figs. 8 and 9 are front and sectional

views respectively of a somewhat different method of securing the bushing to the tape.

Figs. 10 and 11 are perspective views of 55 two other forms of bushings.

14 indicates a fragment of a garment from which the hose supporter is to depend. 15 indicates the upper end of the hose supporter proper. The tape 16 is ordinarily 60 non-elastic, and has its upper ends stitched or otherwise suitably secured to the garment. The hose supporter 15 which is ordinarily of elastic material, is provided with a suitable fastening device 17 having a bar 65 member 18 adapted to be passed through the bushing 19 which is secured to the tape 16.

This bushing 19 is preferably formed of sheet metal and has its end portions 20 folded over the edges of the tape 16, as indicated in Figs. 4 and 5. The body and end portions 20 are then curled or otherwise rolled or formed into a cylindrical bushing, as shown in Figs. 2 and 3. The edges 21 of the ends grip the tape 16 and hold the tape 75 permanently in the position shown in Figs. 1 and 2, the two ends of the tape 16 lying flat together and being adapted to be readily stitched or readily sewed to the garment by anyone. 80

In the form shown in Figs. 6 and 7, the blank 22 which forms the body of the bushing has projecting tangs 23 adapted to embrace the edges of the tape to hold the parts in their proper relative positions as shown 85 in Fig. 6.

In the forms shown in Figs. 8 and 9, the bushing 24 has a plate 25 with slots 26 and 27 through which the ends of the tape are threaded. This bushing and plate is so designed as to permit the tape to be assembled 90 by a hand operation.

In the form shown in Fig. 10, the bushing and plate are similar to those of Figs. 8 and 9, but in this case, I have shown a 95 flange 28 rolled up from the slot 27 so as to afford a rounded bearing edge for the tape.

In the form shown in Fig. 11, the bar 29 is offset somewhat to form the slot 30, and I have provided fingers 31—31 adapted to engage and hold the edges of the tape. 100

I claim:

1. In a hose supporter construction, a loop of tape and a bushing secured in the

- loop and comprising a tubular portion with integrally formed adjacently positioned end members embracing between them the edges of the tape.
5. 2. In a hose supporter construction, a bushing, a tape embracing said bushing, and end members connected to said bushing and embracing the outside of said tape.
3. In a hose supporter construction, a

bushing, a tape embracing said bushing, and 10 end members folded back on said tape and holding said tape to said bushing.

4. In a hose supporter construction, a tubular bushing, a loop of tape embracing said bushing, and end members connected 15 to the ends of the bushing and embracing the edges of the tape adjacent the bushing.

WILLIAM S. HUNKINS.
